W. T. Kosinski

UNITED STATES PATENT OFFICE.

WLADYSLAW T. KOSINSKI, OF BROOKLYN, NEW YORK, ASSIGNOR OF TWO-TENTHS TO HUBERT WEST, OF SAME PLACE.

DEVICE FOR CONVERTING MOTION.

SPECIFICATION forming part of Letters Patent No. 257,344, dated May 2, 1882.

Application filed July 31, 1880. Renewed May 16, 1881. (No model.)

To all whom it may concern:

Be it known that I, WLADYSLAW T. KOSINSKI, a citizen of the United States, residing at Brooklyn, Kings county, New York, have invented certain new and useful Improvements in Devices for Converting Motion; and I do hereby declare the following to be a clear and exact description of the invention, such as will enable others skilled in the art to which it applies to make and use the same, reference being had to the accompanying drawings, and to letters and figures of reference marked thereon, which form part of the specification.

This invention relates to an apparatus in which the reciprocating motion of the lever connected to a chain transmits a rotary motion to the device connected therewith; and it consists in a chain both ends of which are connected to a lever, by means of which the object to be rotated is gripped, and by the alternate reciprocation of the lever a continuous rotary motion imparted to said object.

I have represented my invention as applied to a drill-stock; but it is applicable to chucks, jack-screws, punching-machines, and numerous analogous devices where conversion of motion is desirable.

In the accompanying drawings, Figure I represents the drill-stock; Fig. II, the stock with cap attached and chain and lever connected. Fig. III represents the chain encompassing the stock and cap. Fig. IV represents the chain.

Referring to the drawings, A represents the stock of the drill; B, the cap, secured thereto by a set-screw, H. Around the body of the stock is secured the chain, which consists of a series of links, each series bolted together. The extremities of the chain are provided with links E and F. The former is bolted to or near the extremity of the lever D and the latter a short distance above it, the construction being such that the motion of the lever in one di-

rection its point will grip the stock, while part of the link F will clutch the collar or cap B, by means of which the stock will be partially rotated. By repeating the operation, continuous rotary motion is obtained.

Connected to near the inner and lower extremity of the lever D is the spring I, curved at its free end, the object of which is to be held in frictional contact with the cap, and thereby preventing the turning back of the stock during the interval the grip is being renewed, and preventing lost motion.

When the device is used as a screw-jack, and it should become necessary to reverse the motion or rotation of the screw, the chain is disconnected from the lever by the withdrawal of the bolt connecting the chain to the lever, the operating mechanism is reversed, and the operation continued.

The present invention is based on the same principle shown in my application for a wrench passed for issue, but differs materially in its details and application to various devices enumerated above.

It is evident that in lieu of the chains, steel bands or wire rope may be used with same result.

Having thus described my invention, what I claim as new, and desire to secure by Letters Patent, is—

1. The manner of converting reciprocating into rotary motion by means of chain, steel band, or wire rope, (the ends of which are connected to a lever,) encompassing the object to be rotated by alternate grip and slip motion, as and for the purpose set forth.

2. The combination of the stock and cap, chain, and lever, as described.

W. T. KOSINSKI.
